UNITED STATES PATENT OFFICE.

ARTHUR L. KINGSBURY, OF NORTHAMPTON, MASSACHUSETTS, ASSIGNOR OF
TWO-THIRDS TO ADDISON KINGSBURY, OF SOUTH COVENTRY, AND
FRANK H. ALLEN, OF NORWICH, CONNECTICUT.

MACHINE FOR CORNERING BOX-BLANKS.

SPECIFICATION forming part of Letters Patent No. 530,780, dated December 11, 1894.

Application filed April 27, 1894. Serial No. 509,285. (No model.)

To all whom it may concern:

Be it known that I, ARTHUR L. KINGSBURY, a citizen of the United States, residing at Northampton, Hampshire county, State of Massachusetts, have invented certain new and useful Improvements in Machines for Cornering Box-Blanks, which improvements are fully set forth and described in the following specification, reference being had to the accompanying four sheets of drawings.

The object of this invention is to produce a machine the construction and mechanism of which shall be such that the same, under proper conditions, shall perform upon box blanks, previously cut to size, the operation of "cornering."

Box blanks of the class with which my machine is especially adapted to operate are illustrated in Figures 10 and 11 of the drawings, which drawings are more fully described hereinafter.

In the manufacture of paper boxes, the blanks (usually of straw board) are first cut to the required size and properly "scored," after which they are "cornered" (being then in the condition in which they are illustrated in said figures) when they are ready to be "broken up" and formed into boxes.

The style of blank illustrated in Fig. 10 provides a box the bottom and sides of which are composed of a single piece of straw board and the ends of which are "set on," while the style of blank illustrated in Fig. 11 is used in the construction of box covers or very shallow boxes, the same being composed of a single piece of straw board, the corners being "stayed" by wire clips or strips of cloth or paper, as fully understood by those acquainted with the art of box making.

By reference to Figs. 10 and 11 it will be noted that the corners in the two styles of blanks shown are differently cut in each blank and it is the aim of this invention to produce a machine which shall be adjustable to permit of its cutting both styles of corners illustrated and which shall also have a sufficient range of adjustment to accommodate blanks of all sizes ordinarily used and which shall cut, within a certain range, any depth of corners wished for.

In the drawings, Fig. 1 is a side elevation

of my machine. Fig. 2 is an elevation of the back or rear side and Fig. 3 a plan view of the same. Fig. 4 is a vertical, central sectional view of the upper portion of my machine. Fig. 5 illustrates, principally in section, the means provided for adjusting horizontally (relative to each other) the corner cutting knives of my device. Fig. 6 is a plan view of a vertically movable carriage by means of which vertical reciprocating motion is imparted to the upper blades of the corner cutting knives just referred to. Fig. 7 is a vertical, central, sectional view showing one of certain vertical rods and connected parts, which rods support at their upper ends the said upper blades of the cutting knives of my device. Fig. 8 illustrates, in elevation, the several parts shown in Fig. 7 but shows changed somewhat the positions of several of said parts. Fig. 9 is a plan view of an arm, two of which are employed to assist in supporting that end of the box blanks undergoing the operation of "corner cutting" and in which is located the lower blade of each knife and shows in dotted lines the manner in which said arms are adjustable to cause the cutting knives to properly operate with different styles of work. Figs. 10 and 11 are plan views of box blanks, properly "scored," and illustrate the different styles of corner cutting which it is possible to accomplish with my machine.

My machine, when properly assembled, consists of a stand or table, preferably of considerable weight, upon the top or bed plate of which the box blanks are placed and fed to the corner cutting mechanism, which mechanism is located and supported adjacent to said bed plate.

The reference letter A indicates the bed plate just referred to, which bed plate is supported by two end frames lettered B and C respectively. Frames B and C are tied together at their lower portions by cross frames D and E in which cross frames are provided bearings for the main shaft F of my device. Shaft F has loosely located thereon a driving pulley G, driven by belt G', said pulley being locked to or released from shaft F, by means of a friction clutch H of any suitable style. Upon the end of shaft F is fixedly secured an eccen-

tric J, which latter, through its rod K, imparts motion to the corner cutting mechanism proper of my device, said eccentric being revolved by shaft F on which it is located as 5 above explained, the shaft F being in turn revolved by pulley G when locked thereto by means of clutch H.

To shunt the clutch H on shaft F, to lock or release the same from pulley G, a lever M 10 is centrally hinged as at N (midway the shaft and frame B) one end of which lever M is suitably connected to clutch H and the other end of said lever is pivotally connected to the end of a horizontal rod P, lying in bearings 15 R, provided therefor in the lower portion of the side frame B. Should rod P be slid outward in its bearings, in the direction of the arrow in Fig. 1, the end of lever M pivoted thereto will likewise be carried outward and 20 the same, swinging on its pivot N, will cause its opposite end to swing inward, thereby carrying with it the clutch H and leaving the pulley G free to run idly on shaft F. Should however rod P be slid in its bearings in the 25 direction opposite to that of the arrow in Fig. 1, said lever M will also be caused to rock in a direction opposite to that just described, thereby locking the clutch and driving pulley and causing the latter to revolve on its 30 shaft.

The following described mechanism is provided whereby either hand or foot power, as may be desired, may be employed to operate the clutch H. Beneath the main shaft F, at 35 right angles thereto, and supported in bearings in frames B and C is a rock-shaft S, to which is fixedly secured a foot-lever T. Shaft S extends through its bearings in frame B and bears upon its outer end an arm U the 40 free end of which arm is slotted to receive a stud P' located on rod P. By reference to Fig. 1 it will be seen that when the foot lever T is forced downward it rocks the shaft S, said shaft, through its arm U, causing the 45 rod P to slide in its ways in the direction opposite to that of the arrow in Fig. 1 and thus throw the clutch H into engagement with its pulley G, the various parts being then in the positions illustrated in Fig. 1. As soon as 50 pressure is removed from foot-lever T a spiral spring S' encircling shaft S (Fig. 2) at once causes said shaft and its connected foot lever T and arm U to rock in the opposite direction thus sliding rod P to release the clutch 55 H from pulley G.

To operate clutch H by hand a lever V is provided, hinged midway its length to the frame B the lower end of which lever is pivotally connected to rod P and the free end of 60 which lies conveniently near bed plate A.

It will be seen by reference to Fig. 1 that, when the free end of lever V is forced into the position shown in said figure, the rod R will have been caused to so slide in its bearings as to lock the clutch H and pulley G and 65 it will be as readily understood that, should said lever be drawn outward the clutch H will,

through rod P and lever M, be released from its pulley G. A suitable ratchet catch W is provided on frame B to prevent the lever V, 70 after having been forced backward, from being rocked, by the force of spring S'.

I have provided my machine with two methods for operating the clutch mechanism, as 75 illustrated and described, but it will be seen that only one method is absolutely necessary.

When my machine is properly assembled and in operation the cutting knives proper of my device have a certain vertical reciprocating motion which motion is imparted thereto 80 by means of eccentric J through its rod K, but I do not wish to be understood as confining myself to this particular manner of obtaining that motion, nor to the particular construction illustrated and described of the table 85 and its supporting frames, nor to the manner in which the several elements of the mechanism above described, consisting of main shaft, driving pulley and clutch and eccentric and connected parts, and the manner of controlling 90 said clutch mechanism are assembled, said mechanism being simply illustrated and described as being a very desirable means for producing such reciprocating motion, and the manner which I preferably employ, but it is 95 evident that other styles of stands or tables could be constructed and other means employed for producing the desired vertical movement with equally good results.

Having now described the general construction of the stand or table of my machine, the means provided for imparting motion to the corner cutting mechanism above referred to and the means employed for controlling the driving mechanism, I will proceed to describe 100 the corner cutting mechanism proper, which latter forms the essential feature of my invention.

Secured to the frames B--C at the rear side 105 of my machine (the right hand as shown in Fig. 1) and about midway the height of the side frames, are "V" shaped vertical ways a in which is arranged to travel a carriage b said carriage being pivotally connected midway its length, on its under side, to the upper 110 end of eccentric rod K by which rod said carriage is actuated, the preferred shape of 115 said ways and their relation relative to each other and the manner in which said carriage is caused to travel in its ways by motion imparted thereto from eccentric G, through its rod K, being clearly shown in Figs. 1, 2, 4 and 6.

Carried by carriage b are two vertical rods 120 c to the upper ends of which are secured arms 125 h which carry the upper cutting blades of the knives of my device, as hereinafter fully described. The lower ends of rods c are formed with enlarged heads c' which, when my device is properly assembled, lie in an undercut groove b' extending throughout the length 130 of carriage b, said disks c' being capable of longitudinal adjustment relative to each other in said groove b'.

Supported by frames B—C, somewhat above ways *a* and reaching entirely across the back side of my machine is a cross-frame *d*. The edges of frame *d* provide a horizontal track 5 which supports two vertical shells or collars *e*, the same being supported by arms *e'* located on said shells, which arms so engage track *d* as to support shells *e* thereon but still allow said shells to be moved freely toward or away 10 from each other on track *d*, for a purpose hereinafter explained. This longitudinal movement of shells *e* is accomplished in the following manner:—Each shell *e* is provided between its arms *e'* with a projection *e*² which 15 projections, when the shells are in position on the track, lie in a channel or undercut groove *d'* extending throughout the length of cross frame *d*. Lying within this groove *d'* and passing through each projection *e*² is a rod *f* 20 formed with right and left hand threads, which, when assembled, are in engagement respectively with the threaded projections *e*² of sleeves *e*. Rod *f* is preferably provided with a hand wheel *f'* whereby it may be conveniently rotated and longitudinal displacement 25 of said rod is prevented by means of a stud or pin *d*² which engages the same near its central portion as shown in Fig. 2.

The construction, location and the relative 30 positions of the described track, sleeves, threaded rod and connected parts are clearly shown in Figs. 1, 2, 3, 4, 5, 7 and 8 and by special reference to Figs. 2 and 5 it will be clearly understood that rotation of the threaded rod 35 will cause the sleeves *e* to travel on track *d* either toward or away from each other in accordance with the direction of rotation of said rod.

Supported within shells *e* are what might 40 be termed cylindrical guides *g* in which, when my machine is properly assembled and in operation, the rods *c*, already referred to slide. Guides *g* are prevented from slipping down through sleeves *e* by radial arms *g'* located at 45 their upper portions, and it will be seen by reference to Figs. 1 and 3 that the upper face of each of said arms is flush with the top of the bed plate *A* of my machine.

I have already referred to certain arms (indicated by the letter *h*) supported on the upper ends of rods *c*, which arms bear upon their outer free ends the upper cutting knives *k* of my machine, the shape of which is most clearly shown in Fig. 9. Openings *g*² are provided in arms *g'* to receive the upper cutting knives, a portion of the side wall of each opening being so constructed as to coact with each knife *k* to produce a shearing cut.

The rods *c* are preferably square and the 60 hole through guides *g* in which they slide is correspondingly shaped. With a guide and rod thus constructed it will be seen that the arms *g'* and *h* will always be retained in the same vertical plane relative to each other.

65 In order that my machine may be successfully operated upon the two styles of blanks illustrated in Figs. 10 and 11 it is necessary

that a certain adjustment of guides *g* within sleeves *e* be provided in order that the arms *g'* and *h* may be deflected from the position shown in full lines in the drawings to that shown in dotted lines, or vice versa. To make these adjustments guides *g* are rotated within sleeves *e* and when the desired position of the former is attained a suitable lock as a set 70 screw *e*³, is provided in each sleeve *e* adapted to enter holes *g*³ properly located in the guides *g* to receive the same, as most clearly shown in Figs. 5 and 7, from which figures it will be seen that when the screws *e*³ are in place in 80 guides *g* the latter are positively held against rotation in their respective sleeves.

Assuming that the various parts of my machine thus far described are properly assembled it will be seen, first, that when the machine is in operation, carriage *b* is given a vertical reciprocating motion and that such motion will be communicated through rods *c* sliding in guides *g* to the upper blades of the cutting knives; second, that through the 90 threaded rod *f* actuating sleeves *e*, said sleeves and parts connected thereto may be caused to travel toward or away from each other, as the case may be, the disks *c'* of rods *c* correspondingly traveling in groove *b'* of 95 carriage *b*, and thirdly, by the manner in which the guides *g* and rods *c* are assembled within sleeves *e* the arms *g'* and *h* of each pair may be swung in unison from a common center. The upper knife consists of two distinct cutting edges, located at right angles to each other as shown in the drawings and the lower blade is correspondingly shaped to coact therewith. Should arms *g'* and *h* bearing 100 said knives, be adjusted to the position shown in full lines in the drawings and should a box blank of the class shown in Fig. 10 be placed between the same (said box blank being fed thereto in the direction of the arrow of Fig. 9) it will be seen that, when 110 the knife *k* descends, corners *m*, of the shape shown in said Fig. 10, will be cut in the said blank. Should however the knives be adjusted as shown in dotted lines in Figs. 3 and 9 and a blank of the class shown in Fig. 11 115 fed thereto, in the same manner as just described, it will be seen that the knife *k*, upon descending, will cut out corners *m* of the class shown in said Fig. 11, the difference in the corners in said Figs. 10 and 11 being 120 readily seen by reference to the figures.

In the operation of corner cutting, several blanks properly piled up are fed forward to the knives and, to support that portion of said blanks between the knives, the bed-plate 125 *A* is provided with a central projection *A'* on its rear side. A stop *n* is provided on said projection against which the blanks, being operated upon, abut, said stop being adjustable to regulate the depth of corners to be 130 cut in the blanks. Stop *n* travels in a slot *A*² the lower portion of said stop extending down through the slot. Said stop is operated by means of a rod *o* supported in bearings

beneath the plate A and provided at one end with a hand wheel σ' by which it may be easily rotated and at its opposite end with a screw thread which engages the lower portion 5 of stop n .

When it is desired to use the machine the stop n is so adjusted as to allow the blanks to be introduced between the blades of the knives the necessary distance to produce the 10 desired depth of cut. A scale, as shown in Fig. 3, may be provided near the slot A^2 , whereby the proper adjustment of stop n to produce a desired depth of cut may be readily determined.

15 To avoid the trouble of finding on each blank, or pile of blanks introduced into the machine, the exact places at which the corner cutting shall be done I provide guides or ways p on the bed plate A between which the blanks 20 are accurately introduced to the knives. These ways are of the form shown in Figs. 1, 2, 3 and 4 and are adjustably secured to the table top by means of set screws t lying in slots t' .

25 When in use the guides are secured to the bed plate a distance apart equal to the length of blank to be operated upon and in such location on the said bed plate that those points on the blank at which the corners are to be 30 cut, will be directly in alignment with the corner cutting knives so that when fed forward the blanks will at once find their proper places between said knives.

The ends of the guides p near the front of 35 the machine are preferably turned outward as shown whereby the blanks may be readily fed between the same.

Assuming now that we have a complete machine constructed as described, the various 40 parts properly assembled and adjusted relatively to each other (the knives being set to cut the required style of corner) and that it is desired to operate the machine, the same is first set in motion in the manner already 45 described. Several blanks properly piled up, are fed forward on the bed plate A between the guides p toward the knives, until the blanks abut the stop n which has previously been adjusted to obtain the required depth 50 of cut. When the blades k in their downward motion come in contact with the blanks they at once "corner" the same, when the blanks are removed and the reverse edge of the pile of blanks similarly introduced to the 55 knives to be "cornered."

My machine as a whole is not expensive to produce, is of simple construction and performs rapidly, and in an excellent manner, the operation of "cornering" this class of 60 blanks.

Having described my invention, I claim—

1. In combination with a work supporting table, a reciprocatory support mounted thereon, a cutter upon the support located eccentrically to and movable parallel with the axis 65 of the support, said cutter being movable relatively to the material upon table, with the

support as a center of said movement, and means for reciprocating the support and cutter, substantially as set forth. 70

2. In combination with a work supporting table, a shell or collar secured thereto, a longitudinally movable rotary support within the shell, a cutter secured to the support eccentric to the axis thereof, and means for moving the support, substantially as set forth. 75

3. In combination with a work supporting table, a support thereon, a guide upon the support, an arm upon the support and an arm upon the guide, a cutter upon the arm of the support, and the arm of the guide being provided with an opening, and means for moving the support and for rotating it and the guide, substantially as set forth. 80

4. In combination with a work supporting 85 table, a sleeve carried thereby a guide in said sleeve provided with an angular longitudinal perforation, an angular support through the guide, the upper end of which is provided with a cutter located eccentrically to the axis 90 of the support, a set screw through the sleeve, the inner end of which is adapted to engage with the guide, and to lock it against rotation, and means for reciprocating the support, substantially as set forth. 95

5. In combination with a work supporting table, provided with a cross arm, a pair of reciprocatory supports carried by said cross arm, the upper end of each of which supports is provided with a cutter located eccentrically 100 to the axis of the support, and means for simultaneously moving said supports toward each other and for rotating them upon their axes, substantially as set forth.

6. In combination with a work supporting 105 table provided with an under cut cross bar, of a pair of sleeves upon said bar, each sleeve being provided with a perforated projection which fits within the under cut portion of the bar, an oppositely screw threaded rod through 110 the perforations of the projections, a guide in each sleeve, an arm upon the upper end of the guide provided with a hole, a longitudinally movable rotary support within each guide, the upper end of which is provided 115 with a cutter located eccentrically to the axis thereof, and means for simultaneously reciprocating said supports, substantially as set forth. 120

7. In combination with a work supporting 120 table provided with a cross bar, a pair of longitudinally movable reciprocatory supports carried by said bar, the lower end of each of which is provided with a head, a cutter secured to the upper end of each support, a 125 grooved carriage below the cross bar, the ends of the supports fitting within the grooved portion of the carriage, and means for moving the carriage, substantially as set forth.

ARTHUR L. KINGSBURY.
